UNITED STATES PATENT OFFICE.

FRANK W. HUTCHINS, OF WARREN, OHIO.

PHOTOGRAPHIC CAMERA.

SPECIFICATION forming part of Letters Patent No. 434,046, dated August 12, 1890.

Application filed November 26, 1889. Serial No. 331,656. (No model.)

To all whom it may concern:

Be it known that I, FRANK W. HUTCHINS, of Warren, in the county of Trumbull and State of Ohio, have invented certain new and 5 useful Improvements in Photographic Cameras; and I do hereby declare the following to be a full, clear, and exact description of the invention, such as will enable others skilled in the art to which it pertains to make and 10 use the same.

My invention relates to improvements in photograph-cameras; and it consists in certain features of construction and in combination of parts hereinafter described, and 15 pointed out in the claim.

The scope and purpose of my invention will perhaps be more readily understood if I first outline two varieties of photograph-cameras in common use, to wit, the so-called "view-camera" and the so-called "detective-camera," the former being adapted to ordinary purposes and the latter for instantaneous work. The view-camera usually consists of end sections having respectively attached the lens 20 and the mechanism for holding the sensitized plate, and these end sections are connected by means of a bellows-section, whereby in focusing the end sections can be moved toward or from each other, and one or both 25 of such end sections may be tilted, if need be. This variety of camera has usually a base provided with ways or mechanism of one kind or another by means of which the end sections may be adjusted and held in the desired position. To render the device more 30 conveniently portable, a folding base has sometimes been provided; and to this end sometimes the base has been dispensed with and in place thereof other mechanism substituted—such, for instance, as the falsely-called 35 "lazy-tongs," shown and described in United States Letters Patent No. 364,864 of June 14, 1887. These and other devices had in view not only the distending and collapsing of the 40 camera, but also the tilting or inclining of one or both of the end sections in focusing.

On the other hand, with the detective-camera for instantaneous photographing, no focusing is done except as the operator guesses at the 45 distance of the object and manipulates the camera according to a scale of distances,

whereby an approximate focus sufficiently accurate for the purpose is obtained, and hence with the detective-camera, in place of mechanism for tilting the lens or the sensitized 55 plate, or both, it becomes necessary to hold these members always in parallel planes, so that the axis of the lens shall always be at right angles to the plane of the sensitized plate. To this end the so-called "detective-camera" comprises, usually, a rigid box, in which the movable member or members are inclosed and made to maintain their relative 60 positions with accuracy. As such inclosing-boxes must necessarily be of sufficient size to 65 allow the maximum distention of parts, these cameras are not as compact and convenient for transportation as they would be if they could be collapsed and thereby reduced in size. I have therefore devised the camera 70 illustrated in the accompanying drawings, wherein the bellows or collapsible feature is retained, but accompanied with co-operating mechanism, whereby the end sections are always and accurately held in planes parallel 75 with each other, so that the axis of the lens is always perpendicular to the plane of the sensitized member.

Figure 1 is a side elevation, portions being broken away to show the construction. Fig. 80 2 is an elevation in transverse section on line $x x$, Fig. 1. Fig. 3 is an enlarged perspective in detail.

A and B are the end sections of the camera, the former having attached the lens D, of ordinary construction. Section B is provided with a door B', and is provided internally with whatever mechanism is desired for holding the sensitized plate or for holding rolls of sensitized film, and hence the internal construction 85 of member B may be varied indefinitely, according to circumstances. This matter, however, is well understood in the art, and as I distinctly disclaim any invention on such internal construction of member B and its internal attachments it is not considered necessary further to describe the same.

G is the bellows-section, connecting with members A and B in the usual manner, so that the camera may be distended or collapsed, in 90 which latter position the camera is reduced to perhaps a third or quarter of its maximum 95

length, and hence the small-sized cameras provided for travelers and amateurs could be carried, if need be, in the pocket. For holding the end sections A and B always in parallel plane, so that the axis of the lens shall always be perpendicular to the plane of the sensitized member, I provide the camera on at least three sides, and preferably on four sides, with systems of flat bars arranged like lattice-work—such, for instance, as bars C C', these bars being pivotally connected at the crossing, as shown at c, and pivoted, respectively, to sections A and B, for instance, as shown at c'.

- 15 E and E' are ways or guide-bars connected, respectively, with sections A and B, such ways being provided for the respective systems of lattice-bars, and each system of lattice-bars having pivotally attached at the extremes thereof one or more cross-heads or slides e e' for engaging and sliding on such ways. With such construction it is evident that in distending or collapsing the camera the end sections A and B will always retain their relative parallelism, and hence the axis of the lens having been adjusted in constructing the camera perpendicular to the plane of the sensitized member will always maintain such relative position.
- 20 It is not essential that two cross-heads be employed at each end of the different systems of parallel bars. For instance, with the system shown in the foreground in Fig. 1, suppose bars C C' were severed on line y y and
- 25 that the portions below this line were omitted. There would in such case remain only one cross-head for each way E E'; but the device would still be operative. However, I pre-

fer the construction shown, for the reason that two cross-heads arranged on either side of pivotal point c' distribute the strain and wear more equally.

In the matter of ways, guide-bars, or equivalent mechanism and co-operating slides, cross-heads, &c., adapted to engage and reciprocate thereon there are so many such devices that it is difficult to choose between them, and although the simple construction shown is well adapted to the purpose still any construction of ways or means of guiding and any co-operating mechanism adapted to reciprocate thereon, and at the same time operatively connected with the lattice-bars, would evidently be within the purpose and spirit of my invention:

What I claim is—

The combination of a photograph-camera consisting of end sections having ways thereon and intermediate bellows-section, with lattice-bar sections arranged on at least three sides 6c of the bellows-section, the bars of each section being pivotally connected together at the crossings thereof, and each lattice-bar section being pivotally connected with both end sections and provided with attachments for 65 loosely engaging the ways of the end sections, whereby in manipulating the camera the end sections thereof maintain their parallelism, substantially as set forth.

In testimony whereof I sign this specification, in the presence of two witnesses, this 10th day of October, 1889.

FRANK W. HUTCHINS.
